UNITED STATES PATENT OFFICE

ARTHUR ORLOFF, OF GREEN BAY, WISCONSIN, ASSIGNOR TO NORTHWEST ENGINEERING CORPORATION, OF GREEN BAY, WISCONSIN, A CORPORATION OF WISCONSIN

EXCAVATOR

Application filed March 23, 1928. Serial No. 264,260.

The invention relates to excavators, and more particularly to excavators of the type in which the dipper or bucket travels along guideways provided on a boom.

5 The object of the invention is to provide a rope or cable drive for the bucket to positively move the same in or out along the boom, the drive being provided by a novel arrangement and reeving of the rope or cable 10 for hoisting the boom.

The invention further consists in the several features hereinafter set forth and more particularly defined by claims at the conclusion hereof.

15 In the drawings Fig. 1 is an elevation view of an excavator embodying the invention;

Fig. 2 is a plan view thereof, parts being broken away.

20 In the drawings the numeral 3 designates the body of the excavator, usually embodying a travelling base 4, here shown as equipped with endless treads 5 adapted to be connected up to any suitable source of power, and 6 the rotating base on which the power plant or prime mover is generally mounted. The boom 7 is here shown associated with the rotating base and is mounted 25 for up and down movements relative thereto, or the boom itself may be associated with a rotatable mast on a non-rotating base, as will be readily understood by those familiar with this art, it being noted that in either case the boom is mounted to swing relative 30 to the travelling base and to move down and up for digging or discharging its load.

35 In the present instance a frame member 8, which does not form the subject matter of the present invention, hinged to the rotating base and secured in adjusted position relative thereto by a cable 8', forms an extension of the main base 6 and carries the boom pivot-pin 9.

40 A shaft 10 is journalled in suitable supports on the base 6 and has a hoisting drum 11 and a dragline drum 12 mounted thereon. Each of these drums is equipped in known manner with a clutch for connecting it to shaft 10 and a brake for stopping its rotation and the numeral 13 designates a clutch

and 14 a brake for drum 11, while the numeral 15 designates a clutch for the drum 12 and 16 a brake for said drum. The shaft 10 is driven in any suitable manner from the prime mover (not shown) as by a gear 17 on said shaft meshing with a pinion 18 on a shaft 19 adapted to be connected by any suitable transmission mechanism with said prime mover, such as an electric motor, internal combustion engine or steam engine.

45 According to the present invention the hoisting line 20 associated with drum 11 passes therefrom over a sheave 21, thence over a sheave 22 supported by struts 23 at the outer end of the boom, thence rearwardly over a sheave 24 mounted on the boom pivot-pin 9 and thence to a dead end connection 25 with the dipper 26 whose carriage 27 is provided with rollers 28 mounted to run in trackways 29 provided on both sides of the boom.

50 The construction of the dipper is not shown in detail but it is of known form, having a drop bottom for dumping its load and suitable latch mechanism for holding said bottom closed during digging and releasing the same when the dipper is in position for discharging its load.

55 The dragline 30 associated with the drum 12 passes therefrom outwardly to and over a sheave 31 at the outer end of the boom and thence to the dipper 26 where it is dead ended as at 32.

60 In operation, it is merely necessary, in order to retract the dipper, to wind in on hoisting line 20, thus applying a tension at the rear end of the dipper, drawing it toward the machine. When it is desired to employ line 20 for the purpose of hoisting the boom, it is only necessary to wind in on said line, but retraction of the dipper may be prevented by applying the brake 16 on the drum 12, thus preventing the dragline 30

65 from being payed out and permitting the elevation of the boom to proceed without necessarily altering the position of the dipper lengthwise of the boom. For digging, the dragline, 30 is tensioned by winding it up on its drum 12, causing the dipper to move 70 outwardly into the material while the hoist- 75

ing line 20 is payed out from the then loose drum 11 under the control of the brake 14.

I desire it to be understood that this invention is not to be limited to any particular form or arrangement of parts except insofar as such limitations are included in the claims or necessitated by the prior art.

What I claim as my invention is:

1. In an excavator, the combination with a boom mounted for up and down and lateral swinging movements, of a dipper mounted to travel back and forth along the boom, a cable operatively connected with the boom at a point forward of its mounting and at a point adjacent its mounting and then with the dipper for raising and lowering the boom and retracting the dipper, a cable for moving the dipper outwardly during digging, and means for controlling said cables including a brake to restrain the movement of said last named cable while raising the boom by first named cable.

2. In an excavator, the combination with a supporting platform, of a hoisting drum mounted thereon, a boom connected with said platform for up and down movements, a dipper mounted to travel back and forth along the boom, a cable on said hoisting drum operatively connected with the forward and rear portions of said boom and secured to said dipper for retracting the same, a second drum, and a cable on said second drum associated with the forward end of the boom and with said dipper for moving it outwardly during digging and means for controlling said drums including a brake for said second drum to restrain the movement of said last named cable while raising the boom by said first named cable.

3. In an excavator, the combination with a boom mounted for up and down movements, of a dipper mounted to travel back and forth along the boom, a cable connected with the boom at points forward and adjacent its mounting and then with the dipper for raising and lowering the boom and retracting the dipper, a cable for moving the dipper outwardly during digging, drums for said cables, and separate controls for said drums including a brake for one of said drums to restrain the movement of said last named cable while raising the boom by said first named cable.

4. In an excavator, the combination with a boom mounted for up and down and lateral swinging movement, of a dipper mounted to travel back and forth along the boom, a cable connected with the forward and rear portions of the boom and then with the dipper for raising and lowering the boom and retracting the dipper, a cable for moving the dipper outwardly during digging, a power-driven shaft, drums for said cables mounted on said shaft, and clutches and brakes for controlling said drums the brake for the

drum of the second named cable restraining the movement of said cable while raising the boom by said first named cable.

In testimony whereof, I affix my signature.
